UNITED STATES PATENT OFFICE.

JOESEPH G. PLACETTE, OF PORT ARTHUR, TEXAS, ASSIGNOR TO THEODORE PLACETTE,
OF PORT ARTHUR, TEXAS.

BURNER.

1,342,226.

Specification of Letters Patent.

Patented June 1, 1920.

Application filed February 26, 1919. Serial No. 279,341.

To all whom it may concern:

Be it known that I, JOSEPH G. PLACETTE, a citizen of the United States, residing at Port Arthur, in the county of Jefferson and State of Texas, have invented certain new and useful Improvements in Burners, of which the following is a specification.

My invention relates to improvements in burners adapted to use a liquid fuel, such as crude oil or the like.

An important object of the invention is to provide means whereby the liquid fuel, such as crude oil, is introduced into the presence of steam, to be thoroughly atomized and vaporized thereby, forming a gaseous mixture which is highly efficient in use.

A further object of the invention is to provide an apparatus of the above mentioned character, which is simple in construction, inexpensive to manufacture, and convenient in use.

Other objects and advantages of the invention will be apparent during the course of the following description.

In the accompanying drawing, forming a part of this specification, and in which like numerals are employed to designate like parts throughout the same,—

30 Figure 1 is a central vertical longitudinal sectional view through the burner, associated elements being in elevation,

Fig. 2 is an end elevation of the same,

35 Fig. 3 is a transverse sectional view taken on line 3—3 of Fig. 1,

Fig. 4 is a bottom plan view of the top member of the burner casing, and

Fig. 5 is a horizontal sectional view taken on line 5—5 of Fig. 1.

40 In the drawings, wherein for the purpose of illustration is shown a preferred embodiment of my invention, the numeral 10 designates a burner casing or head, as a whole, comprising upper and lower casing sections 11 and 12, which are preferably cylindrical. These casing sections have chambers 13, which are cylindrical, and have their inner open ends arranged adjacent to each other.

50 Disposed between the casing sections 11 and 12, is a partition plate 14, serving to separate the chambers 13, and provided with a central vertical opening or port 14, disposed concentric to the chambers 13.

55 The casing sections 11 and 12 are secured

together by bolts 15, also passing through openings 16, formed in the partition plate 14.

The upper casing section 11 is provided at its forward portion with a gas outlet 60 opening 17, having an inclined upper wall 18. The opening 17 has forwardly diverging side walls 19, as shown.

A steam supply opening or port 20 leads into the top of the upper chamber 13, and 65 a portion of this opening is screw-threaded, for receiving the screw-threaded end of a steam supply pipe 21. This steam supply pipe has connection with a steam pipe 22, through the medium of a coupling 24. The 70 pipe 22 is equipped with a valve 24.

Leading into the lower end of the lower or oil chamber 13 is an opening or port 25, one end of which is screw-threaded, for the reception of the screw-threaded end of 75 an oil supply pipe 26. This oil supply pipe has connection with an oil pipe 27, through the medium of a T-coupling 28. A valve 29 is connected in the pipe 27.

Connected with the rear end of the pipe 80 21 is valve 30 connected with an elbow 31, having connection with the rear end of the pipe 26.

The operation of the burner is as follows:

The valve 30 is normally closed, and the 85 valves 24 and 29 suitably opened. Oil under suitable pressure, such as crude oil, passes through the pipe 27, and through the pipe 26 into the oil chamber 13. This oil is then forced in a vertical stream through 90 the opening 14', into the atomizing and mixing chamber 13 above the plate 14. This vertical stream of oil projects upwardly and impinges against the upper wall of the casing section 11, and is sprayed thereby, 95 the same falling toward the plate 14. This sprayed oil is subjected to the action of the steam supplied to the pipe 21, and is further atomized and vaporized thereby. The 100 gaseous mixture discharges through the opening 17 and is ignited at the outlet end of such opening.

When the burner is stopped, valves 24 and 29 are closed. Valve 30 may now be opened, and steam will be supplied into and through 105 the pipe 26, upon the valve 24 being again opened. The steam is supplied through the pipe 26 to blow out the oil which accumulates within the pipe 26.

It is to be understood that the form of 110

my invention herewith shown and described is to be taken as a preferred example of the same, and that various changes in the shape, size, and arrangement of parts may be resorted to without departing from the spirit of the invention or the scope of the subjoined claim.

Having thus described my invention, I claim:

10. A burner of the character described comprising a casing having a substantially cylindrical mixing chamber and an oil pre-heating chamber, and an outlet opening leading from the mixing chamber, a partition plate extending between said cham-
- 15.

bers and provided substantially centrally thereof with an upwardly extending passage, means for supplying oil under pressure into the oil chamber whereby the oil will be forced through the upwardly extending opening and impinge against the upper wall of the mixing chamber to be sprayed thereby, and means of introducing steam into the mixing chamber.

In testimony whereof I affix my signature 25
in presence of two witnesses.

JOSEPH G. PLACETTE.
